United States Patent Office.

JACOB DOURSON, OF COLUMBUS, OHIO.

Letters Patent No. 98,359, dated December 28, 1869.

IMPROVED BEDSTEAD AND LOUNGE.

The Schedule referred to in these Letters Patent and making part of the same.

To all whom it may concern:

Be it known that I, JACOB DOURSON, of Columbus, in the county of Franklin, and State of Ohio, have invented certain new and useful Improvements in Combined Bedstead and Lounge; and do hereby declare that the following is a full, clear, and exact description thereof, reference being had to the accompanying drawings, and to the letters of reference marked thereon, making a part of this specification.

The nature of my invention consists in the construction and arrangement of a bedstead and lounge, as will be hereinafter fully set forth.

In order to enable others skilled in the art to which my invention appertains, to make and use the same, I will now proceed to describe its construction and operation, referring to the annexed drawings, in which—

Figure 1 is an end view, showing my invention in the position for a lounge;

Figure 2 is an end view, showing its position as a bed; and

Figure 3 is a side view of the double joint in the mattress-frame.

A represents the frame of my bedstead and lounge, which frame may be made in any manner desired, so as to have end pieces, and no high sides.

B represents the mattress-frame, which, at each end, in the centre, is provided with a double joint, C, as seen in fig. 3.

The mattress-frame B is hinged to the bedstead A by means of a metal plate, D, at each end, said plates

being, at one end, pivoted to the mattress-frame, and at the other to the bedstead-frame.

The plates D D, with the bedstead and mattress-frames, are so arranged, that when the mattress-frame is turned back, as shown in fig. 1, its front side will be about even with the front side of the bedstead-frame, and the rear half of the mattress-frame can be turned up, so as to form the back of the lounge, the double joint C allowing the mattress to be bent in proper shape for the same.

When the mattress-frame is turned forward, as shown in fig. 2, to form a bed, the said frame extends equally on both front and rear sides of the bedstead-frame, so as to be evenly and completely supported by the bedstead-frame.

Having thus fully described my invention, What I claim as new, and desire to secure by Letters Patent, is—

The combination of the bedstead-frame A, mattress-frame B, double joints C, and plates D, all constructed and arranged substantially as and for the purposes herein set forth.

In testimony that I claim the foregoing, I have hereunto set my hand, this 8th day of November, 1869.

JACOB DOURSON.
